(57) **CLAIM**

The ornamental design for a combined wet/dry vacuum cleaner with a detachable blower and accessory storage, as shown and described.

DESCRIPTION

FIG. 1 is an isometric front perspective view of a wet/dry vacuum with a detachable blower and accessory storage;

FIG. 2 is a top view thereof;

FIG. 3 is a front elevational view thereof;

FIG. 4 is a back elevational view thereof;

FIG. 5 is a side view thereof; and,

FIG. 6 is a side view showing the side opposite that shown in FIG. 5.

The broken lines in the Figures are for the purpose of illustrating exemplary environmental structure and forms no part of the claimed design.
